ASPIRATOR SPRAY HEAD

John J. Anderson, Kenosha, Wis., assignor, by mesne assignments, to Emery Industries, Inc., Cincinnati, Ohio, a corporation of Ohio

Filed Nov. 2, 1965, Ser. No. 87,983

Term of patent 14 years

(Cl. D91—1)

Fig. 1.

Fig. 2.

Fig. 3.

Fig. 4.

Fig. 5.

FIG. 1 is a top plan view of my aspirator spray head showing my new design;

FIG. 2 is a side elevation view of the aspirator spray head;

FIG. 3 is a front elevation view;

FIG. 4 is a perspective view of the aspirator spray head; and

FIG. 5 is a rear elevational thereof.

The dominant features of my design reside in the portions shown in full lines.

I claim:

The ornamental design for an aspirator spray head, substantially as shown and described.
